UNITED STATES PATENT OFFICE.

CATHERINE C. COOLEY, OF OMAHA, NEBRASKA.

DESIGN FOR A DOLL.

55,503.

Specification for Design. Patented June 22, 1920.

Application filed January 13, 1920. Serial No. 351,262. Term of patent 7 years.

To all whom it may concern:

Be it known that I, CATHERINE C. COOLEY, a citizen of the United States, residing at Omaha, in the county of Douglas and State of Nebraska, have invented a new, original, and ornamental Design for a Doll, of which the following is a specification, reference being had to the accompanying drawing, forming a part thereof.

The figure is a front view of a doll, showing my new design.

I claim,—

The ornamental design for a doll, as shown.

In testimony whereof, I have affixed my signature in presence of two witnesses.

CATHERINE C. COOLEY.

Witnesses:

HIRAM A. STURGES,
ARTHUR H. STURGES.
